FIG. 2

FIG. I

FIG. 3

UNITED STATES PATENT OFFICE

2,448,273

CONTROL

George C. Pearce, Dayton, Ohio, assignor to General Motors Corporation, Dayton, Ohio, a corporation of Delaware

Application December 11, 1944, Serial No. 567,896

23 Claims. (Cl. 200—140)

1

This invention relates to controls, and more particularly to a switch adapted to control the energization of the heaters of an oven in an electric range or the like in response to temperatures within the oven. The switch may also be used to control the energization of any electric circuit for any type of domestic appliance or the like.

An object of this invention is to provide a switch of simple construction, in which the parts are rugged and may be made with relatively large tolerances without affecting the efficiency of the switch.

Another object of this invention is to provide a simple control in which an extremely small dimensional change of the power element operates the snap action mechanism without any hesitation and with a high degree of accuracy.

Further objects and advantages of the present invention will be apparent from the following description, reference being had to the accompanying drawings, wherein a preferred form of the present invention is clearly shown.

In the drawings:

Fig. 1 is a longitudinal cross-section taken along the line 1—1 of Fig. 2;

Fig. 2 is a transverse cross-section taken along the line 2—2 of Fig. 1; and

Fig. 3 is a cross-section taken along the line 3—3 of Fig. 2.

A switch embodying features of my invention includes, in general, a first frame 10, conveniently channel-shaped in cross-section. It also includes a second frame 11, conveniently also channel-shaped in cross-section. Fulcrum means, in the form of a pin 12, holds the frames together at one end. Spring means are provided at the other end of the frame members 10 and 11. This spring means may comprise two helical coils 13, each mounted around the pins 14, which pins are secured to the first frame 10. The springs 13 urge the frame members 10 and 11 away from each other, and tend to swing them apart, about the fulcrum 12. A rotatable shaft 15 is in threaded engagement at 16 with the frame 10, and is in axially fixed bearing engagement at 17 with the frame 11. This last bearing engagement includes a disc 18 fixed to the shaft 15, and bearing against the side of the frame 11. The springs 13 urge the frame 11 against the disc 18. Rotation of the shaft 15 varies the angle between the frames 10 and 11, for the purpose of varying the temperature setting, as hereinafter more fully explained. The shaft 15 may be rotated by a suitable manually actuatable knob, not shown, which may be secured

2

to the shaft 15 at the end 19. Such knob may carry suitable temperature indications.

A snap switch 20 is carried by the first frame 10. A thermostatic power element 21 is carried by the second frame 11 and engages the snap acting switch at 22. The thermostatic power element 21 may be connected by a tube 23 with a liquid bulb, not shown, which may be placed in the oven to be heated by electric elements controlled by the switch 20. Expansion of the liquid in the bulb introduces liquid into the power element 21, and expands the same. This moves the point 24 against the lever 25, at 22, of the snap acting switch 20, and actuates the same. Manual rotation of the shaft 15 varies the angle between the frames 10 and 11, and varies or selects the temperature setting at which the snap switch 20 operates.

The snap switch 20 may include one or more snap acting U-shaped conductor blades 30. Each of these blades 30 has a first leg 31 secured to the frame 10 at 32. Each leg 31 is secured at 32 by means of a rivet, which in turn is secured to its respective conductor bar 33, which passes through a base 34 of insulating material, and terminates at 35. A respective connector 36 threadedly engages each bar 33, to which a respective electric line may be secured. Each bar 33 is also secured to the base 34 at 33a and 37 by means of rivets. The base 34 is carried by the frame 10, being secured thereto by screws 34a and bolts 44.

Each of the conductor blades 30 also has a second leg 38 which is in an on and off snapping engagement with a respective stationary contact 39, carried by the frame 10. Each contact 39 is carried by a respective conductor bar 40. Each bar 40 passes through the base 34 and terminates at 41, where each bar 40 is provided with a connector 42 in threaded engagement with the bar 40. Each leg 38 is limited in its off position travel by a respective Z-bar 43, of insulating material. Each Z-bar 43 is secured to the frame 10 by the bolt 44.

Thus, as shown, the thermostatic switch is a double pole switch, with two input connectors 36 and two output connectors 42. The number of poles may be varied, if desired.

The U-shaped conductor blades 30 are preferably formed of sheet metal, and the legs 31 and 38, together with their bridging member, are all of an integral piece of sheet metal.

Movable spring means are provided for creating a longitudinal compression strain in each of the legs 31, for the purpose of producing on and off snap action in the second legs 38. Preferably this

takes the form of a tension helical spring 50, which is secured at one end to a metal bar 51, which bar in turn is secured by rivets 51a to the bar 52 of insulating material. The bar 52 is riveted at 53 to the blades 30, to cause them to move in unison. The other end of the spring 50 is secured to the lever 25 at the orifice 54. The lever 25 is carried by the frame 10 through the medium of an inverted U-shaped leaf spring 55 which is secured to the pins 56 by means of bolts 57. A relatively rigid U-shaped backing plate 55a is interposed between the spring 55 and the pins 56. The pins 56 are secured to the frame 10 by screws 56a. The spring 55 causes the lever 25 to fulcrum about the spring 55 with a bias towards the thermostatic power element 21, whereas the power element 21, when it expands, fulcrums the lever 25 in opposition to the spring 55.

When the lever 25 swings counterclockwise, in Fig. 1, due to cooling of the oven, or the like, the lever 25 reaches a point where the upper end of the spring 50 and bar 52 snap to the left as indicated in dotted lines in Fig. 1. This action causes the contacts 60, at the lower ends of legs 38, to move into contact with the respective stationary contacts 39 as indicated in dotted lines in Fig. 1. When this occurs, current can pass from each connector 36 through bars 33 and rivets 32 to the respective conductor blades 30, and from thence, through contacts 60, 39, bars 40 and connectors 42 to the heaters in the oven which are then energized. The temperature at which this occurs is determined by the rotational position of shaft 15 and its manually actuatable knob. When the oven is heated to a predetermined upper limit, determined by the same position of shaft 15 and its knob, the liquid from the bulb expands power element 21 a sufficient amount to swing the lever 25 clockwise, when the upper end of spring 50 is snapped to the right to move the bar 52 against the head of stop screw 61. This opens the contacts 60 away from the contacts 39. This deenergizes the heaters in the oven at the upper temperature limit.

By using member 43 as a stationary contact support, and making 43 of conducting material, while making 39 and 40 of insulating material, the switch may be used to control the operation of a refrigerator or the like, where electrical energization is required when the thermostat reaches a predetermined upper temperature limit, and where electrical deenergization is required when the thermostat reaches a predetermined lower limit.

In operation, the user rotates shaft 15, by means of its knob, from the off position to the desired temperature setting. This swings the frames 10 and 11 away from each other about fulcrum means 12, usually a sufficient amount to cause lever 25 to swing counterclockwise to the on position. This causes spring 50 and bar 52 to snap to the left and brings contacts 60 and 39 together to energize the heaters in the oven, as shown in dotted lines in Fig. 1. As the temperature in the oven rises, liquid flows from the 65 thermostatic bulb in the oven through tube 23 to expand power element 21. When the selected temperature is reached, the element 21 has expanded sufficiently to move lever 25 clockwise to a point where spring 50 and bar 52 snap to the right to the position shown in full lines in Fig. 1. This opens contacts 60 and 39, thus deenergizing the heaters in the oven. When the oven cools to the lower temperature limit, the element 21 contracts sufficiently to snap the 75

bar to the left. This starts the second heating cycle, which may be repeated until the knob of shaft 15 is turned to the off position.

While the form of embodiment of the invention as herein disclosed constitutes a preferred form, it is to be understood that other forms might be adopted, as may come within the scope of the claims which follow.

What is claimed is as follows:

1. A switch device comprising: a first frame; a second frame; fulcrum means holding said frames together; a snap acting switch on said first frame; a thermostatic power element on said second frame and engaging said snap acting switch; and a manually movable element engaging said frames and adjusting the angle between said frames to vary the temperature setting.

2. A switch device comprising: a first frame; a second frame; fulcrum means holding said frames together; a snap acting switch on said first frame; a thermostatic power element on said second frame and engaging said snap acting switch; and a manually rotatable shaft engaging switch; and a manually rotatable shaft engaging said frames and adjusting the angle between said frames by rotation of said shaft to vary the temperature setting.

3. A switch device comprising: a first frame; a second frame; fulcrum means holding said frames together; a snap acting switch on said first frame; a thermostatic power element on said second frame and engaging said snap acting switch; and manually rotatable shaft in threaded engagement with one of said frames and in axially fixed bearing engagement with the other of said frames, rotation of said shaft adjusting the angle between said frames to vary the temperature setting.

4. A switch device comprising: a first frame; a second frame; fulcrum means holding said frames together; spring means engaging said frames and tending to vary the angle between said frames; a snap acting switch on said first frame; a thermostatic power element on said second frame and engaging said snap acting switch; a manually rotatable shaft in threaded engagement with one of said frames and in axial engagement with the other of said frames in opposition to said spring means, rotation of said shaft adjusting the angle between said frames to vary the temperature setting.

5. A switch device comprising: a frame; a stationary contact secured to said frame; a snap acting U-shaped conductor blade having a first leg secured to said frame and a second leg having its non-connected end portion in snapping engagement with said stationary contact; and movable spring means creating a longitudinal strain in said first leg.

6. A switch device comprising: a frame; a stationary contact secured to said frame; a snap acting U-shaped conductor blade having a first leg secured to said frame and a second leg having its non-connected end portion in snapping engagement with said stationary contact; a lever fulcrumed on said frame; and spring means carried by said lever and connected to the yoke portion of said conductor blade to create a longitudinal strain in said first leg.

7. A switch device comprising: a frame; a stationary contact secured to said frame; a snap acting U-shaped conductor blade having a first leg secured to said frame and a second leg having its projecting non-connected end portion in snapping engagement with said stationary contact; a lever fulcrumed on said frame and urged

to swing in one direction; a movable element engaging said lever to urge said lever in the opposite direction; and spring means carried by said lever and connected to the yoke portion of said conductor blade to create a longitudinal strain on said first leg.

8. A switch device comprising: a frame; a stationary contact secured to said frame; a snap acting U-shaped conductor blade having a first leg secured to said frame and a second leg having its projecting non-connected end portion in snapping engagement with said stationary contact; a lever fulcrumed on said frame; a thermostatic element engaging said lever to swing said lever in response to temperature conditions; and spring means carried by said lever and connected to the yoke portion of said conductor blade to create a longitudinal strain on said first leg.

9. A switch device comprising: a first frame; a stationary contact secured to said frame; a snap acting U-shaped conductor blade having a first leg secured to said frame and a second leg in snapping engagement with said stationary contact; a lever fulcrumed on said frame; spring means carried by said lever and connected to said conductor blade to create a longitudinal strain on said first leg; a second frame; fulcrum means holding said frames together; a thermostatic element carried by said second frame and engaging said lever to swing said lever in response to temperature conditions; and means to vary the angle between said frames to adjust the temperature setting.

10. A switch device comprising: a first frame; a stationary contact secured to said frame; a snap acting U-shaped conductor blade having a first leg secured to said frame and a second leg in snapping engagement with said stationary contact; a lever fulcrumed on said frame; spring means carried by said lever and connected to said conductor blade to create a longitudinal strain on said first leg; a second frame; fulcrum means holding said frames together; a thermostatic element carried by said second frame and engaging said lever to swing said lever in response to temperature conditions; and a manually rotatable shaft engaging said frames and adjusting the angle between said frames by rotation of said shaft to vary the temperature setting.

11. A switch device comprising: a first frame; a stationary contact secured to said frame; a snap acting U-shaped conductor blade having a first leg secured to said frame and a second leg in snapping engagement with said stationary contact; a lever fulcrumed on said frame; spring means carried by said lever and connected to said conductor blade to create a longitudinal strain on said first leg; a second frame; fulcrum means holding said frames together; a thermostatic element carried by said second frame and engaging said lever to swing said lever in response to temperature conditions; and a manually rotatable shaft in threaded engagement with one of said frames and in axially fixed bearing engagement with the other of said frames, rotation of said shaft adjusting the angle between said frames to vary the temperature setting.

12. A switch device comprising: a first frame; a stationary contact secured to said frame; a snap acting U-shaped conductor blade having a first leg secured to said frame and a second leg in snapping engagement with said stationary contact; a lever fulcrumed on said frame; spring means carried by said lever and connected to said conductor blade to create a longitudinal strain

on said first leg; a second frame; fulcrum means holding said frames together; a thermostatic element carried by said second frame and engaging said lever to swing said lever in response to temperature conditions; second spring means engaging said frames and tending to vary the angle between said frames; a manually rotatable shaft in threaded engagement with one of said frames and in axial engagement with the other of said frames in opposition to said second spring means, rotation of said shaft adjusting the angle between said frames to vary the temperature setting.

13. A switch device comprising: a frame; a plurality of stationary contacts secured to said frame; a plurality of snap acting U-shaped conductor blades each having a first leg with its non-connected end portion in snapping engagement with a different one of said stationary contacts; a bar bridging said blades to cause simultaneous motion of said blades; and movable spring means applying a column loading upon the yoke portion of the first legs for creating longitudinal strain on said first legs.

14. A switch device comprising: a frame; a plurality of stationary contacts secured to said frame; a plurality of snap acting U-shaped conductor blades each having a first leg secured to said frame and a second leg in snapping engagement with a respective one of said stationary contacts; a bar bridging said blades to cause simultaneous motion of said blades; a lever fulcrumed on said frame; and spring means carried by said lever and connected to said conductor blades to create longitudinal strain on said first legs.

15. A switch device comprising: a frame; a plurality of stationary contacts secured to said frame; a plurality of snap acting U-shaped conductor blades each having a first leg secured to said frame and a second leg in snapping engagement with a respective one of said stationary contacts; a bar bridging said blades to cause simultaneous motion of said blades; a lever fulcrumed on said frame; a thermostatic element engaging said lever to swing said lever in response to temperature conditions; and spring means carried by a said lever and connected to said conductor blades to create a longitudinal strain on said first legs.

16. A switch device comprising: a first frame; a plurality of stationary contacts secured to said frame; a plurality of snap acting U-shaped conductor blades each having a first leg secured to said frame and a second leg in snapping engagement with a respective one of said stationary contacts; a bar bridging said blades to cause simultaneous motion of said blades; a lever fulcrumed on said frame; spring means carried by said lever and connected to said conductor blades to create a longitudinal strain on said first legs; a second frame; fulcrum means holding said frames together; a thermostatic element carried by said second frame and engaging said lever to swing said lever in response to temperature conditions; and means to vary the angle between said frames to adjust the temperature setting.

17. A switch device comprising: a first frame; a plurality of stationary contacts secured to said frame; a plurality of snap acting U-shaped conductor blades each having a first leg secured to said frame and a second leg in snapping engagement with a respective one of said stationary contacts; a bar bridging said blades to cause simul-

taneous motion of said blades; a lever fulcrumed on said frame; spring means carried by said lever and connected to said conductor blades to create a longitudinal strain on said first legs; a second frame; fulcrum means holding said frames together; a thermostatic element carried by said second frame and engaging said lever to swing said lever in response to temperature conditions; and a manually rotatable shaft engaging said frames and adjusting the angle between said frames by rotation of said shaft to vary the temperature setting.

18. A switch device comprising: a first frame; a plurality of stationary contacts secured to said frame; a plurality of snap acting U-shaped conductor blades each having a first leg secured to said frame and a second leg in snapping engagement with a respective one of said stationary contacts; a bar bridging said blades to cause simultaneous motion of said blades; a lever fulcrumed on said frame; spring means carried by said lever and connected to said conductor blades to create a longitudinal strain on said first legs; a second frame; fulcrum means holding said frames together; a thermostatic element carried by said second frame and engaging said lever to swing said lever in response to temperature conditions; second spring means engaging said frames and tending to vary the angle between said frames; a manually rotatable shaft in threaded engagement with one of said frames and in axial engagement with the other of said frames in opposition to said second spring means, rotation of said shaft adjusting the angle between said frames to vary the temperature setting.

19. A switch device comprising: a frame; an insulation base on said frame; a snap acting U-shaped conductor bar having the non-connected end portion of one leg secured to a first side of said base; a connector extending from said leg to the second side of said base; a stationary contact on said first side of said base; a connector from said contact to the second side of said base; said snap acting U-shaped conductor bar having the non-connected end portion of its second leg in off and on contact with said stationary contact; and spring means creating an on and off bias in said U-shaped conductor bar.

20. A double pole switch mechanism including two anchorages insulated from each other, a movable member including two U-shaped thin metal members each having an unanchored leg and one leg anchored to one of said anchorages and a bridging means bridging the yokes of said U-shaped members but having means for electrically insulating them from each other, a spring

means acting upon the bridging means for imposing a column loading upon the two anchored legs, two switch contact means insulated from each other each cooperating with the unanchored leg of one of said U-shaped members, and means for moving a portion of said spring means in a direction transverse to the column loading to cause the movable member to trip to operate the unanchored legs.

5 21. A switch mechanism including two anchorages, a movable member including a yoke and a plurality of thin metal leg members extending in one direction from the yoke with separate leg members connected to each anchorage, switch contact means cooperating with a remaining leg member, tension spring means having one end connected to said yoke and having the other end extending in generally the same direction as said anchored legs, and means for laterally moving 15 20 said other end of said spring means to operate the movable member.

22. A control including a first frame, a second frame, a fulcrum means pivotally connecting the frames together, a control device mounted on said 25 first frame, a power element mounted on said second frame and having means for engaging and operating said control device, and a manually movable element engaging said frames and adjusting the angle between said frames to vary the 30 relationship between the change in dimension of the power element and the operation of the control device.

23. A control including a frame, a control device mounted upon said frame, a snap-acting U-shaped thin metal blade having the non-connected end portion of the first leg secured to said frame and the non-connected end portion of its second leg cooperating with said control device, a movable spring means for applying a column 35 40 loading upon said blade to column load said first leg, and operating means for moving said spring means to cause the snap-action movement of said blade.
